(57) **CLAIM**

The ornamental design for an post driving bit for a hammer drill, as shown and described.

DESCRIPTION

FIG. 1 is a front perspective view showing my new design; FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a front view thereof of my new design with a hammer driving the post into the ground.

The dash-dash broken lines depict environmental structure and form no part of the claimed design. The dash-dot-dash broken lines define the bounds of the claim and form no part thereof.

1 Claim, 7 Drawing Sheets
